UNITED STATES PATENT OFFICE.

SPENCER OTIS, OF CHICAGO, ILLINOIS.

LOCOMOTIVE TERMINAL COALING AND SANDING STATION.

Application filed June 5, 1922. Serial No. 565,975.

To all whom it may concern:

Be it known that I, SPENCER OTIS, a citizen of the United States, residing at Chicago, in the county of Cook and State of Illinois, have invented certain new and useful Improvements in Locomotive Terminal Coalting and Sanding Stations, of which the following is a specification.

This invention relates to a locomotive terminal, and particularly to that part of a terminal which supplies material, such as coal and sand, to locomotives.

One object of the invention is to store materials of the kind stated not only in bulk to be drawn upon as needed, but also in subdivided charges having dimensions and positions which will admit of instant delivery of predetermined quantities to locomotives to be supplied.

Another object is to so arrange bulk storage space and subdivided charging receptacles that gravity can be employed for passing the material to the bulk storage space from rolling stock which brings the material in, and from the subdivided charging spaces which deliver measured quantities of material to locomotives, and thereby reduce to a minimum the occupancy of trackage by the rolling stock or the detention of the rolling stock at the station.

Still another object is to provide for conditioning and distributing material in a station of the kind described, and particularly sand to be supplied therein.

In carrying out the invention, I employ surface trackage for bringing in the material in bulk, a sub-surface bulk storage space for material, particularly fuel, receiving the material by gravity from rolling stock upon said surface trackage, subdivided delivery or provisional storage space, with super-surface location, and delivery equipment adapted to discharge measured quantities of material into locomotives to be replenished while occupying surface trackage; and dirigible elevating and conveying means for removing material from the bulk storage space and delivering it, selectively, to the individual subdivisions of delivery or provisional storage space. The invention also contemplates coordinating with the desired system of storage and distribution of fuel, drying bins for sand, supplied by the elevating and conveying means from cars on the surface trackage; main storage sand bins

supplied by gravity from said drying bins; and provisional storage or distributing bins supplied, preferably through pneumatic conveyors, from said main sand storage bins, and elevated in position and equipped with delivery spouts that adapt them to charge sand into locomotives occupying the same surface trackage occupied during fuel loading, so that fuel and sand supplies can be delivered simultaneously.

Preferably, the provisional storage and delivery bins for both fuel and sand, and surface trackage for locomotives receiving therefrom are duplicated on opposite sides of the bulk storage space and elevating and distributing apparatus, and the delivery units are multiplied along these sides in order that a plurality of locomotives may take station simultaneously at each side, and the elevating and distributing apparatus, both for fuel and sand, can serve all provisional storage and delivery containers alike.

In the accompanying drawings—

Figure 1 is a vertical transvers section of a coaling and sanding terminal, the section being taken on the line 1^x—1^x of Figure 2.

Figures 2 and 3 are, respectively, a side elevation and a plan view of the same.

Figure 4 is a detail view of delivery controlling elements of the fuel and sand supply spouts; and

Figure 5 is a detail view showing one method of elevating sand from the bulk storage to the provisional storage or delivery units.

1, 1, represent surface level trackage related to a sub-surface bulk fuel storage space 2 in a manner to permit unloading by gravity into such space fuel contained in rolling stock on said trackage. The storage space 2 is preferably of a form and construction which will adapt it to confine water, so that fuel in the form of coal, when stored in large volume, can be safeguarded against spontaneous combustion.

3 represents a dredging and elevating bucket, for instance of the clam-shell type, suspended by winding rope 4 from trolley 5 adapted to traverse a bridge 6, which is in turn movably mounted upon the usual tracks 7. The winding of the rope 4, the traversing of trolley 5, and movements of bridge 6 are assumed to be under voluntary control of an operator in a cage 8, so that a charge of

fuel or other material picked up by the bucket 3 can be elevated to a super-surface position and then moved and deposited at will over any desired point within the range 5 of the elevating mechanism.

9 represents provisional storage pockets for fuel which extend inwardly to points that adapt them to be charged with fuel through means of the bucket 3, and which 10 terminate in spouts 10 presented in position to deliver the contents of any pocket instantly to a locomotive tender, such as suggested at A, standing on one of the surface tracks 11. Spouts 10 are provided with 15 suitable valves or closures 10^a through means of which to determine the time of their discharge.

12 represents drying pockets for sand adapted to be charged by the bucket 3 with 20 sand brought into the terminal in cars upon the tracks 1. These drying pockets communicate through spouts 13, having controlling valves 13^a, with bulk storage sand tanks 14 to which the sand is delivered, after 25 drying. From bulk sand tanks 14 the sand is elevated through pneumatic tubes 15 to provisional sand storage or unit delivery tanks 16, where it is held, properly conditioned, in predetermined subdivisions of 30 volume suitable for charging locomotives entering upon the tracks 11. Each delivery sand tank 16 has a spout 17 in position for delivery to a locomotive, as aforesaid, and these spouts have some suitable form of 35 controlling valve as suggested at 17^a, through means of which the time of discharge of the contents of the tanks may be determined at will.

40 Any suitable means may be employed for causing sand to rise through the pneumatic tubes 15. By way of illustration the air blast nozzle 18 in ejector relation to the pipe 15 is shown in Figure 5.

45 The system of surface trackage 1, through means of which supplies are brought into the terminal, is preferably arranged in duplicate, and the capacity of the sub-surface storage space 2 correspondingly enlarged; and bulk storage sand tanks 14, drying 50 pockets 12, fuel delivery pockets 9, and sand delivery tanks 16 are preferably arranged in pairs, while surface trackage 11 is duplicated on opposite sides of the terminal in order that two lines of locomotives may be 55 charged simultaneously, the trackage and delivery pockets or tanks being arranged so

that a plurality of locomotives on each track may be served at one time.

By the system of sub-surface bulk storage of fuel with gravity discharge thereinto 60 from the surface level supply tracks, and gravity discharge from the distributing pockets or tanks, the detention of rolling stock on any of the tracks is reduced to a minimum of time. By having the elevating 65 crane adapted to transfer materials as described, selectively, to any of the receiving pockets or tanks, the latter can be kept filled by more or less constant operation of the crane, so that the pockets and tanks are 70 ready at all times to deliver charges of material to the locomotives, measured by the capacity of the pockets.

The expression "surface trackage," "surface level, supply track" or equivalent expression found in the foregoing specification and in the sub-joined claim, is to be understood as indicating trackage receiving supply cars and locomotives to be charged from the normal trackage of the system. Such 75 tracks, at the coaling and sanding station, whether for presentation of locomotives to be supplied or receiving cars with supplies for the terminal, may be on, or above, or below the actual horizontal level of the main 80 tracks with which they connect, or on different levels with each other, the spirit of this invention residing in the relation of this trackage to the storage space which permits 85 gravity discharge thereinto from said trackage, and of the distributing storage spaces above which permit gravity discharge to 90 locomotives occupying said surface trackage.

I claim:

95 In a locomotive supply station, a sub-surface bulk storage space, surface level trackage adapted to receive rolling stock in position to deliver by gravity into said space, a locomotive charging track adjacent said space, elevated charging receptacles adapted 100 to deliver material to locomotives occupying said charging track, an elevating means selectively operable to transfer material from the bulk storage space to the respective charging receptacles, storage tanks for sand 105 also adapted to be charged by said elevating means, and delivery sand tanks supplied from said storage sand tanks.

Signed at Chicago, Illinois, this 2nd day of June, 1922.

SPENCER OTIS.
